UNITED STATES PATENT OFFICE.

BYRON F. GLOVER, OF CHICAGO, ILLINOIS.

SNOW-LOCOMOTIVE.

SPECIFICATION forming part of Letters Patent No. 593,466, dated November 9, 1897.

Application filed January 9, 1897. Serial No. 618,549. (No model.)

To all whom it may concern:

Be it known that I, BYRON F. GLOVER, a citizen of the United States, residing at Chicago, in the county of Cook and State of Illinois, have invented a certain new and useful Improvement in Snow-Locomotives, of which the following is a specification.

My invention relates to machines adapted for hauling sledges or the like over snow or ice roads and involving, usually, a hollow traction-wheel which is driven so as to propel the machine and is heated from its interior so as to melt down or pack the snow and thereby form such roads.

Prominent objects of my invention are to secure the greatest economy in operating the machine and in heating its traction-wheel; to facilitate and increase the draft of the furnace without involving any additional expense; to mount the traction-wheel so as to permit of one of its sides falling slightly, as required by the uneven surface of the road, without causing a corresponding jarring or jolting motion of the frame of the machine, and to provide a simple and improved construction of traction-wheel.

To the attainment of the foregoing and other useful ends my invention contemplates providing means for supplying heated atmospheric air and conducting such heated air to the interior of the hollow traction-wheel. By thus heating the traction-wheel by means of heated air rather than by the steam itself the accumulation of water of condensation in said wheel is avoided, it being here observed that such an accumulation of water in the wheel is exceedingly undesirable and difficult to handle. As a preferred arrangement, the air is heated by means of the steam exhausted from an engine employed to drive the machine and then both the exhaust-steam and the air from the wheel are directed into the smoke-stack of the furnace, which supplies heat for the boiler, so as to increase the draft therein.

In the accompanying drawings, Figure 1 is a side elevation of a snow-locomotive embodying my invention. Fig. 2 is a plan view of the same. Fig. 3 is a side elevation, on a larger scale, of the traction-wheel and mounting therefor. Fig. 4 is an end elevation of a portion of the same, showing certain portions

in cross-section, as indicated by line 4 4 in Fig. 3. Fig. 5 is a plan view of the traction-wheel. Fig. 6 is a vertical section of the same, taken on line 6 6 in Fig. 5. Fig. 7 shows in section a modified construction of the periphery of the traction-wheel, and Fig. 8 represents in elevation the apparatus for heating air by means of steam.

The frame of the machine or engine-truck A can for certain purposes be mounted upon wheels, but as a preferred arrangement it is supported upon runners B. The engine-truck A carries a suitable upright boiler C, having a steam-dome C' and an engine D, by which the traction propelling wheel or wheels can be driven. The hollow traction-wheel E could be of any suitable construction adapted for such machines. It is found very desirable, however, to have the traction-wheel provided with a number of pointed teeth arranged upon its periphery, and as a matter of improved construction for providing such teeth the traction-wheel is constructed with a number of peripheral seats, Figs. 5, 6, and 7, adapted to hold these teeth removably in place. The teeth are provided with three longitudinal sides and the seats therefor are provided with opposing side faces or walls, which are inclined toward one another correspondingly with the inclination of the sides of the teeth, by which arrangement the teeth may be slid from the end of the seat into place thereon and may be removed therefrom so as to replace or repair the same. In Fig. 6 the seats 1 for the teeth 2 are shown arranged below the periphery 4 of the wheel and the inclined opposing faces 3 are formed integral with said periphery. In Fig. 7 the seats are provided by the periphery 4 of the wheel and the inclined faces 3 are provided by the flanges 5, which are bolted upon the periphery. The construction shown in Fig. 6 I consider preferable, inasmuch as it permits the traction-wheel, with the desired teeth seats and faces, to be readily and inexpensively cast in one piece, and also allows the wheel to be used with the teeth removed when so desired, in which case the inclined faces 3 furnish a small amount of traction. These longitudinal sides are also desirably equal in width, whereby all three sides of each tooth may be placed upon its seat, thereby permitting each pointed edge to

be successively used until worn down. The teeth 2 can be arranged upon the periphery of the traction-wheel so as to extend entirely across the width of the latter, if desired, or 5 in any other preferred way, and the same can be held in place upon their seats in any suitable manner. As a preferred arrangement, however, the traction-wheel is composed of a number (three, for instance, as shown in Fig. 10 5) of annular sections E' and the teeth are arranged at intervals upon each section so that the teeth of one section lie opposite the spaces between the teeth of the next adjacent sections. The teeth of each section may be 15 slipped into place and the sections E' can then be secured together, the periphery of each section thus serving as a stop for preventing slippage toward it of the teeth in the adjacent sections. As one arrangement for securing 20 the annular sections E' together, each is provided with inwardly-extending peripheral flanges 6, (shown in dotted lines in Fig. 5,) which are bolted together, and as a means of preventing the teeth of the outside annular 25 sections from slipping out the rings 7 are bolted to the outer flanges 6 of such sections.

The traction-wheel E is desirably connected with the propelling attachment F, which latter is pivotally connected with the beams a', 30 which form the sides of the body-frame of the machine. In order to allow the traction-wheel to pass easily over portions of the road which are higher on one side than on the other, the bearings or boxes G for said wheel work 35 in substantially vertical guideways, such as the slots 8, which are formed in the members F', composing the traction propelling attachment, whereby one side of the traction-wheel may slide downwardly without wrenching 40 the frame and also whereby the tilting frame may be lifted clear of the traction-wheel when it is desired to disconnect the latter from the machine. One of the meeting surfaces formed by the top of the box or 45 bearing G and the lower side of the frame-piece F', forming the upper end of the slot, is desirably curved or rounded, thereby permitting an easy rolling or wabbling motion of the bearing-box. Thus in Figs. 3 and 4 50 the portion f of the beam F', which forms the upper end of the slot 8, is shown provided with a curved rib f'.

The traction-wheel E may be driven by any suitable connection, a desirable arrangement 55 being that shown in the figures, wherein the traction-wheel is provided with a gear-wheel E'', which meshes with a gear-wheel H, mounted on the transverse shaft H', which forms the pivotal connection between the body of the 60 machine and the tilting frame, and is driven by the engine D.

The hollow traction-wheel E is interiorly heated by means of heated air. The air could be heated in any suitable manner and led to 65 the interior of the wheel by suitable connections. As an exceedingly economical arrangement, I have shown the exhaust-pipe D'

of the engine D connected with a suitable air-heater J, which is connected with the interior of the traction-wheel. The heater illustrated 70 involves a series of air-pipes j, (see Fig. 8,) having their ends fitted in the disks j', and a cylindrical shell or casing J', inclosing the pipes j and disks j' and provided with air inlet and outlet pipes 9 and 10. The exhaust- 75 steam enters the cylinder J by means of the pipe D', attached thereto, and circulates around the pipes j, so as to thoroughly heat the air passing through the latter. The outlet-pipe 10 is connected with the interior of 80 the traction-wheel through the hollow axle of the latter by means of the flexible connector 11^a, which allows a vertical play on the part of the wheel. The air from the interior of the wheel could be allowed to pass into the 85 open air, but as a matter of further improvement the wheel is connected with the interior of the smoke-stack, as by the pipes 11 and 12, whereby the current of air assists the draft 90 of the furnace. Obviously a suitable circulation of air through the heater and traction-wheel will occur whether the air is turned into the outside atmosphere or into the smoke-stack of the furnace, for in the first instance the air, being still slightly warm, will contract 95 and so tend to create a draft in the wheel toward the outlet-port thereof, and in the second instance the rising fumes of combustion will tend to create a vacuum or partial vacuum 100 in the hollow wheel by reducing the pressure in the connection between the smoke-stack of the furnace and the wheel, and thereby tend to draw the air out of the latter. However, as an additional means of inducing a circulation of heated air through the hollow 105 traction-wheel, I have shown a fan or blower K connected to the end of the pipe 9 and arranged to force or drive the heated air through the hollow traction-wheel, and as a matter of still further improvement I have shown the 110 heater J connected by means of pipes 11 and 13 with the furnace smoke-stack, so that the exhaust-steam may pass into the latter after leaving the heater. By such arrangement the exhaust-steam and heated air passing 115 into the furnace smoke-stack increases materially the draft of the furnace and thereby facilitates combustion therein. By such arrangement also the gaseous currents in the exhaust-steam pipe and in the furnace smoke- 120 stack tend to create a vacuum or partial vacuum outside of the wheel by lowering the air-pressure in the connection leading thereto, and thereby tend to induce a circulation of the heated air through the wheel. 125

The driving or forcing fan or blower K could of course be employed alone to circulate the air through the wheel, and in some instances said fan or blower can be dispensed with altogether and the exhaust-steam pipe, 130 the furnace smoke-stack, or some other suitable pressure-reducing device could be employed alone as a means of causing the desired air circulation.

I could of course provide for the disposal of the exhaust-steam from the heater and for the circulation of the heated air through the hollow traction-wheel in other ways without departing from the spirit of my invention; but I regard the foregoing as an exceedingly simple, economical, and satisfactory arrangement for accomplishing such ends.

Inasmuch as a certain amount of the exhaust-steam is found to condense in the heater J, a suitable tank L is situated below the latter and connected with the same by means of the pipe 14, (shown in dotted lines in Fig. 1,) whereby such condensed steam may be collected and fed again into the boiler.

What I claim is—

1. The combination, in a snow-locomotive, of a hollow traction-wheel, and means for supplying heated air connected with the traction-wheel so as to communicate with the interior thereof, as set forth.
2. The combination, in a snow-locomotive, of a hollow traction-wheel, means for supplying heated air connected therewith, means for inducing a circulation of the heated air through the hollow wheel, and a furnace or the like which is connected with the traction-wheel so as to receive the air issuing from the latter, as set forth.
3. In a snow-locomotive, the combination of a hollow traction-wheel; means for supplying heated air connected therewith; and means for inducing a circulation of the heated air through the hollow traction-wheel.
4. The combination with the hollow traction-wheel in a snow-locomotive, of an air-heater connected therewith, and a driving fan or blower connected with the air-heater, as set forth.
5. The combination with the furnace and boiler, the engine, and the hollow traction-wheel in a snow-locomotive, of an air-heater which is provided with an air connection adapted to communicate with the interior of the traction-wheel and is connected with the engine so as to receive the exhaust therefrom, and with the furnace so as to increase the draft therein, as set forth.

6. In a snow-locomotive, the combination of a hollow traction-wheel; means for supplying heated air connected therewith; and means for inducing a circulation of the heated air through the hollow wheel, comprising pressure-increasing and pressure-reducing devices connected respectively to opposite sides of the wheel.

7. A traction-wheel comprising a plurality of annular sections detachably secured together and respectively provided with a series of circumferentially-arranged and transversely-extending teeth-seats depressed below the wheel-periphery and arranged out of register with one another in adjacent sections, and a series of removable teeth adapted to fit upon the depressed teeth-seats, and adapted also to be held upon their seats by the adjacent annular wheel-sections, and to be removed therefrom only when such annular sections are detached from one another, as set forth.

8. The traction-wheel provided with peripheral seats having inwardly-inclined longitudinal faces rising therefrom, and provided with removable teeth constructed with three longitudinal sides which are substantially equal in width and which are adapted to fit upon said seats between the inclined faces thereof, as set forth.

9. In a snow-locomotive, the combination with the furnace, the boiler and the engine, of an air-heater connected with both the engine and the furnace, whereby the exhaust from the engine is utilized for heating the air and also for increasing the draft of the furnace; a hollow traction-wheel having its interior in communication with the air-chamber of the air-heater, and also with the furnace so as to increase the draft of the latter; and means for inducing a circulation of air through the air-heater, and the traction-wheel, and into the furnace, substantially as set forth.
